UNITED STATES PATENT OFFICE.

THOMAS STEWART HARRIS, OF MINNEAPOLIS, MINNESOTA.

PAVEMENT.

1,280,995.

Specification of Letters Patent.

Patented Oct. 8, 1918.

Application filed May 17, 1917. Serial No. 169,230.

To all whom it may concern:

Be it known that I, THOMAS STEWART HARRIS, a citizen of the United States, and a resident of Minneapolis, in the county of 5 Hennepin and State of Minnesota, have invented certain new and useful Improvements in Pavements, of which the following is a specification.

My invention relates to pavements.

- 10 It is common practice to lay wood blocks contiguous to each other between retaining walls such as the side or interior walls of buildings, the curbs of streets, the beams or girders of bridges, etc. Such blocks 15 naturally expand under weather or induced moisture conditions. A limited amount of such expansion can be absorbed in the body of the pavement by spacing the blocks from each other, in common practice about a 20 quarter of an inch, the space being ordinarily filled with a yielding pitchy substance. The amount of expansion which can thus be absorbed, however, is relatively small and in many instances the maximum 25 space which it is practicable to provide between the blocks is far from being sufficient to absorb the expansion of the wood. In many uses also there is a serious objection to a pitchy filler between the blocks in that 30 upon expansion of the wood the filler is forced out upon the tread surfaces of the blocks. Such situations are found in the floors of workshops and the like, and frequently also in streets. In cases of these 35 latter kinds no means have heretofore been suggested that I am aware of for avoiding the injurious effects of block expansion. In many such cases heavy reinforced concrete building walls have been pushed out of 40 plumb by the expanding blocks, it is safe to say, as much as ten or twelve inches, and in roadways where the curbing has been strong enough to withstand the tremendous pressure the entire wood pavement has 45 risen from its base so that the crown of the pavement has been sometimes five or six feet higher than its normal position. The upward extension of such pavements for a distance of several feet is quite common.
- 50 Such conditions of excessive expansion are not to be found in all localities, the same usually being due to the presence of a sub-soil adapted to retain large quantities of water in association with the pavement for 55 considerable periods; but the same kind

of trouble and difficulty exists to a greater or less extent wherever wood paving blocks are employed between confining walls, and, although there may be no appreciable rupturing or displacement of such walls for a 60 length of time, the danger of excessive block swelling is always present, and in many instances the retaining walls are under considerable strain at various times due to the expansion pointed out. 65

It is needless to say that where the pavement has buckled or swelled above its base the street must be closed to traffic, and that in most cases the relaying of substantially 70 the entire affected area is required.

The principal objects of the present improvements are to provide a pavement susceptible of any degree of expansion whatsoever without injury to the retaining walls and without the loss of service of the principal portion of the pavement or floor; to provide means in a pavement which will at all times indicate to interested persons the amount of expansion actually taking place whereby suitable provision may promptly 75 be made for maintaining the desired character of the pavement without any substantial loss of service thereof; to provide means whereby the pavement may be readily and easily maintained in serviceable condition; 80 and to provide means also which may be of simple form, easy of manufacture and installation, and which may constitute a part of the pavement itself without changing the general character of the tread surface 85 thereof. Other objects and advantages will appear hereinafter. 90

In the accompanying drawings, which form a part of this specification, I have illustrated such means in combination with 95 wood blocks and retaining walls of well known form. In these drawings Figure 1 is a sectional view illustrating the improved pavement or floor between walls of a building; 100

Fig. 2 is a fragmentary top plan of the pavement of Fig. 1;

Fig. 3 is a sectional fragment showing the position of one of the expansion joint pieces after a relatively small amount of 105 block expansion has taken place;

Fig. 4 shows in section the elements of Fig. 3 with one of the adjusting strips removed, the flat tread surface of the pavement being restored; 110

Figs. 5 and 6 are fragmentary sections of the pavement of Fig. 1 showing how continued expansion of the paving is relieved without pressure upon the retaining wall; 5 and

Fig. 7 is a sectional, fragmentary perspective showing the application of these improvements in street paving.

Referring to Figs. 1 to 6 inclusive the 10 blocks 10, base 11, and retaining or abutment walls 12 and 13 are to be considered as being of any approved and well known construction. They illustrate a flat floor or pavement in a building or in any other position 15 between relatively fixed walls. Between the body of the pavement (comprising the blocks 10 and half blocks 10^a) and the abutment walls 12 and 13 respectively I provide a pair of substantially telescoping 20 expansion joint members 15 and 16, they being preferably wood pieces of considerable length, say eight to twelve or more feet, the pieces being substantially rectangular in cross section in the forms illustrated when 25 normally together, as in Figs. 1, 2 and 4. They extend along the abutment wall and form a marginal border for the pavement body. These two pieces 15 and 16 may be conveniently formed by taking a rectangular 30 piece of wood, preferably the height of the blocks 10, and sawing the same diagonally, as on the line 17, the line 17 preferably not extending to the vertical sides of the piece, the angle or slant of the line or surface 17 35 being such that the part 16 will slide or move upon the part 15 and whereby the part 16 will be directed against the wall, as 12, at such an angle that it will slide upward thereon when expansion of the wood forces 40 the same beyond the position thereof shown in Fig. 5.

The expansion joint pieces 15 and 16 are suitably positioned directly against the retaining wall, as 12. In the form shown they 45 constitute a part of the pavement itself. The blocks 10 and half blocks 10^a preferably terminate on a line as 18, Fig. 2, parallel with the longitudinal edges of the expansion joint piece 16, which line may well be coincident with such edge, as shown at 19, Fig. 5. However, for purposes of more readily 50 adjusting the pavement surface under relatively slight expansion movements of the blocks I preferably provide one or more adjusting strips, as 20 and 21, preferably co-extensive in length and height with the pieces 15 and 16 and lying between them and the main body of the pavement. From Fig. 3 it will be observed that under a relatively slight expansion the piece 16 is forced 55 upward slightly, whereupon if one of the adjusting pieces, as 20, be removed the part 16 will readily assume its normal position as shown in Fig. 4. Under further expansion 60 the strip 21 may similarly be removed. In 65

laying the pavement a suitable number of such adjusting strips may be employed to fill any space which may occur adjacent to the pieces 15 and 16, thus avoiding the necessity of trimming off the ends of blocks 70 10, 10^a.

Referring to Fig. 7, the curb 25, base 26, and block 10 are of well known form and construction. The expansion joint pieces 15 and 16 and the adjusting strips 20 and 21 75 are of the same form respectively as in the other figures. The functions and operations of the parts are also the same as those already described.

A particularly important feature of these 80 improvements is in the fact that under continued and excessive expansion of the blocks the retaining walls, as 12, 13 or 25, or of whatever form they may be, are at all times relieved from pressure, the expansion strains 85 being diverted from such walls, the pieces or blocks one after the other riding upward upon the slanting surface 17 upon the expansion joint piece 15, such parts and blocks, in the absence of any attention on the part 90 of interested persons, simply creeping up along the wall, falling over, and forming a row of loose blocks along the edge of the pavement, at a place where they are substantially out of the path of traffic or, in a 95 building, away from the floor space being occupied. Thus the efficiency of the floor or roadway is not destroyed or seriously if at all affected by any such expansion strains.

According to these improvements repairs 100 following excessive expansion may be made most expeditiously and at relatively slight cost, it being simply necessary to rejoin the edge of the block paving into a substantially straight line, using the half blocks 10^a there 105 present, inserting one or more strips 20, 21 as required, and replacing the sliding joint member 16.

Another feature of advantage is in the 110 fact that interested persons are promptly informed by the elevation of the part 16 that expansion of the pavement is taking place, whereupon such attention to the pavement or to conditions affecting its expansion may be given as the occasion may suggest. Thus, 115 for instance, in shops so paved excessive sprinkling of the pavement with water may be avoided when undue expansion is being occasioned thereby. It sometimes happens that automatic sprinkler systems flood such 120 floor surfaces, and, where the pavement has been constructed according to hitherto practices, before interested persons became aware of danger from block expansion the retaining walls have often been greatly injured 125 or a buckling of the pavement has taken place. In all such cases and also where expansion is due to natural climatic or soil conditions the normal condition of the retaining walls and the continued utility of 130

the pavement are maintained in a pavement made according to the improvements herein set forth.

The invention is not limited to the construction specifically illustrated and described herein, and I contemplate all modifications and departures therefrom as fall within the scope of the appended claims.

I claim:

- 10 1. The combination of wood blocks forming a pavement body, an abutment wall spaced from said body, and an expansion joint device between the abutment wall and said pavement body with paving blocks contiguous to the joint device, said expansion joint device including a member having a surface slanting upward toward the abutment wall over which slanting surface the paving blocks contiguous thereto will slide 20 under the influence of expansion of the paving body.
- 15 2. The combination of wood blocks forming a pavement body, an abutment wall adjacent thereto and spaced therefrom, said paving body terminating in a line substantially parallel with the abutment wall, and an expansion joint device between the abutment wall and the pavement body and adapted to divert from the abutment wall 30 expansion strains developed in the pavement body, said expansion joint device including a pair of interfitting wood pieces having coöperating sliding surfaces normally on an upward incline toward the abutment wall, 35 the inclination of the piece adjacent to the abutment wall being such that paving blocks in the paving body adjacent thereto will slide upward thereon under expansion strains.
- 40 3. The combination of paving blocks

forming a paving body, an abutment wall adjacent thereto and spaced therefrom, an expansion joint piece extending along the abutment wall and having an upwardly inclining surface and positioned between said 45 wall and the pavement body, a second expansion joint piece having a similar slanting surface resting upon the slanting surface of said first mentioned expansion joint piece, said expansion joint pieces forming a 50 marginal border for the pavement body.

4. The combination of paving blocks forming a pavement body, an abutment wall adjacent thereto and spaced therefrom, the pavement body having an edge portion substantially parallel with the abutment wall, a pair of coöperating expansion joint pieces between the pavement body and the abutment wall, said pieces having facing surfaces extending upwardly toward the abutment wall, and an adjustment piece in strip form also between the abutment wall and the pavement body.

5. The combination of an abutment wall, a base for a pavement extending to the abutment wall, a wood strip running along said abutment wall and resting on said base, said strip having a surface inclining upward and toward the wall and forming an angle with the bottom of said strip, a second strip resting upon the first mentioned strip and adapted to slide on said inclined surface, and wood pavement elements contiguous to said second mentioned strip, the arrangement being such that upon expansion of said pavement elements said second strip is forced upward on said slanting surface whereby such strains of expansion are diverted from the abutment wall.

THOMAS STEWART HARRIS.
